UNITED STATES PATENT OFFICE.

JONATHAN F. LATHAM, OF PAINT ROCK, ALABAMA, (ADMINISTRATOR OF EPHRAIM LATHAM, DECEASED,) ASSIGNOR TO LIONEL D. SAXTON, OF PHILADELPHIA, PENNSYLVANIA.

CAR-COUPING.

SPECIFICATION forming part of Letters Patent No. 530,697, dated December 11, 1894.

Application filed January 23, 1894. Serial No. 497,758. (No model.)

To all whom it may concern:

Be it known that EPHRAIM LATHAM, deceased, formerly residing in the city of Washington, District of Columbia, did invent a new and useful Improvement in Car-Couplings, which improvement is fully set forth in the following specification and accompanying drawings.

This invention relates to an improvement in a car coupling which is formed of a draw-head, a knuckle, a slide for locking said knuckle, a pivotal lever for withdrawing said slide and a spring for returning or advancing the same, said lever having its axial-end mounted outside of the draw head, passing freely through said slide and having its free end likewise outside of the draw head, whereby both ends of the lever are accessible for the insertion and removal of the axial pin and the connection and disconnection of the operating chain of said lever and the latter may be grasped at its free end to close the locking slide should the spring be weak or broken for temporarily effecting the coupling, as will be hereinafter set forth.

Figure 1 represents a longitudinal horizontal section of a car coupling embodying the invention. Fig. 2 represents a longitudinal vertical section on line x, x , Fig. 1. Fig. 3 represents a front end view thereof. Fig. 4 represents a transverse section on line y, y , Fig. 1.

Similar letters of reference indicate corresponding parts in the several figures.

Referring to the drawings: A designates a hollow draw-head, on the forward end of which is an arm B, on which is mounted the knuckle or jaw C, whose heel D is adapted to engage with the side of the locking slide E, which latter is freely fitted within the draw-head.

F designates a spring which bears against the inner end of the slide E, and against the block G, the latter being seated against the shoulders H formed by the junction of the cylindrical and angular portion J and K of the draw-bar, the tendency of said spring being to force the slide in the direction toward the heel D, and into engagement with the same, thereby locking the knuckle, it being

evident that when the opposite coupler advances, the operation is such that the two knuckles engage and said heel interlocks with the head of the slide E, whereby the knuckle is controlled and the coupling of the car is effected in an automatic and reliable manner. In the slide is a slot L, which freely receives the lever M, one end of which is pivotally connected with the ear N on the wall of the draw-head, and the other end is free to be grasped or operated by the chain P to which a suitable lever may be attached if so desired, the opposite sides of said wall being slotted as at Q Q', for the play of said lever M, it being noticed that when it is desired to uncouple the cars, the lever M is drawn back, whereby motion is imparted to the locking slide in the direction from the heel D, so as to clear the latter, whereby the heel is released and the knuckle is uncontrolled by said slide it being evident that said knuckle may now swing outwardly, say to the position shown in Fig. 1, whereby it is disconnected from the opposite knuckle, or vice-versa, and the uncoupling thereby effected. When the lever M is let go, the slide returns to its normal position, so that the heel may again press against the same, when the knuckle is forced back so that said heel again engages with said slide and the knuckle interlocks with the latter as previously stated. As the ends of the lever protrude through the slots Q, Q' outside of the draw head they are readily accessible for connection with and disconnection from the draw head A and the chain P and the free end of the same may be grasped for advancing the slide should the spring be weak or broken and effecting the coupling for temporary purposes.

Having thus described the invention of EPHRAIM LATHAM, deceased, what is claimed as new, and desired to be secured by Letters Patent, is—

1. In a car coupling, a draw head having a knuckle, a slide for controlling said knuckle, a swinging lever for withdrawing said slide, and an ear on the outside of the draw head, said lever passing freely through a slot in said slide, and slots in the sides of the draw head,

and protruding through the latter at both ends, one end being pivotally connected with said ear, and the parts combined substantially as described.

- 5 2. A car coupling consisting of the draw head A, with the arm B, the knuckle C on said arm, the slide E adapted to interlock with the heel of said knuckle, the swinging lever M passing freely through the slot L in the slide, 10 the ear N on the drawhead, and the side slots Q, Q', in the wall of the draw bar, said lever hav-

ing both ends protruding through said side slots outside of the draw bar, and having one end pivoted on said ear, the parts being combined substantially as described.

JONATHAN F. LATHAM,
Administrator of the estate of Ephraim Latham, deceased.
